CLAIM

The ornamental design for a drip tray for beverage dispenser, as shown and described.

DESCRIPTION

FIG. 1 is a front perspective view of drip tray for a beverage dispenser showing our new design;

FIG. 2 is a front elevation view thereof;

FIG. 3 is a right side elevation view thereof;

FIG. 4 is a left side elevation view thereof; and,

FIG. 5 is a top plan view thereof.

Bottom forms no part of claimed design.

The broken lines in the drawings are included for the purpose of illustration and form no part of the claimed design.
